INVENTOR.

UNITED STATES PATENT OFFICE.

GEORGE A. WHITING, OF NORTH ATTLEBORO, MASSACHUSETTS, ASSIGNOR
TO GREENLEAF & CROSBY COMPANY, OF FLORIDA.

DESIGN FOR A PIN OR SIMILAR ARTICLE.

SPECIFICATION forming part of Design No. 34,154, dated March 5, 1901.

Application filed February 1, 1901. Serial No. 45,658. Term of patent 7 years.

To all whom it may concern:

Be it known that I, GEORGE A. WHITING, a citizen of the United States, residing at North Attleboro, in the county of Bristol and State 5 of Massachusetts, have invented a certain new and original Design for a Pin or Similar Article, of which the following is a specification, reference being had therein to the accompanying drawings.

10 Figure 1 is a plan view of my pin-body, and Fig. 2 a side elevation of the same.

As shown in the drawings, the leading or material feature of my design consists in the representation of the fruit *a* of the orange-tree inclosed within an encircling branch *e*, which forms the pin periphery. A cluster of

orange-leaves *b c d* is represented as surmounting the fruit *a* and radiate from near the pin center to its circumference.

It is evident that this design is applicable 20 to all classes of pins and other similar articles.

Having described my invention, what I claim as new, and desire to secure by Letters Patent, is—

The design for a pin, or similar article, as 25 herein shown and described.

In testimony whereof I have affixed my signature in presence of two witnesses.

GEORGE A. WHITING.

Witnesses:

EMELYN I. TAFT,
HORATIO E. BELLOWES.
